UNITED STATES PATENT OFFICE.

FRED REISS, OF NEW YORK, N. Y., ASSIGNOR TO EAGLE PENCIL COMPANY, OF NEW YORK, N. Y., A CORPORATION OF DELAWARE.

PACKAGE FOR PENCILS, PENHOLDERS, AND LIKE ARTICLES.

Application filed September 26, 1925. Serial No. 53,766.

This invention relates to the packing of pencils, penholders and the like for storage, shipment and display, and its chief object is to provide a package for such articles which will adequately protect the same in shipment and storage and yet permit attractive display of the articles when on sale. Another object is to provide a package which can be manufactured at low cost and in which the articles can be rapidly packed and securely held and protected. To these and other ends the invention comprises the novel features hereinafter described.

One form of the invention is illustrated in the accompanying drawings, in which

Fig. 1 is a front view of the package as arranged for display of the articles, which in the present instance are lead pencils.

Fig. 2 is a front view of the cover, folded out flat.

Fig. 3 is a front view of the package with the cover in place.

Fig. 4 is a section on line 4—4 of Fig. 3.

The back or support 10 is made of cardboard or other suitable material of proper stiffness, and is slightly wider than the length of the pencils 11 or other articles which are to be carried thereby. The support is provided with a pair of oppositely extending longitudinal slits 12, 13, terminating at top and bottom in transverse slits 14, 15, to provide a pair of opposed tongues 16, 17, to receive and hold the pencils or other like articles 11. For this purpose the tongues are provided with apertures 18, 19, so arranged that when the tongues are bent forwardly, as shown in Fig. 4, the apertures will be aligned transversely, into which the pencils can be slipped and held securely thereby. The support may be provided with a hole 20 at the top to permit hanging it up to display the articles and permit instant removal of any one of them, or it may have at the back a folding stay (not shown) to permit it to stand on a flat surface, or it may have both.

The cover 21, to be used when the goods are not on display or exposed for sale, comprises a slip of cardboard 22, creased or scored along the lines 23, Fig. 2, these lines being spaced slightly farther apart than the width of the card or support 10. In height the cover is slightly narrower than the length of the vertical slits 12, 13 in the sup-

port. To apply the cover, it is placed over the pencils or other articles and its ends are folded back flat at the edges of the support and are slipped into the slits 12, 13, the ends overlapping each other, more or less, in front of or under the narrow slot 24 between the slits just mentioned. The articles mounted on the support or back 10 are thus protected and kept clean and attractive in appearance. The cover is held securely in place by its resiliency or stiffness, which makes it necessary to employ a positive effort to remove it, and accordingly the cover will not come off accidentally. Movement of the cover longitudinally of the support 10 is limited by the slits 14—14, 15—15, as well as by friction, so that displacement upwardly or downwardly far enough to expose one of the articles is virtually impossible if the cover is made wide enough to fit rather snugly between said slits, even though the uppermost and lowermost articles are close to the upper and lower ends of the supporting tongues in which they are mounted. In the drawing the cover is shown considerably narrower than the vertical space between the aforesaid slits, in order to show the latter more clearly.

The goods are shipped and stored with the cover in place, thereby protecting the articles against soiling or scratching, which would impair their salability. When they are to be displayed for sale the cover is removed by drawing the ends out of the retaining slits, leaving the articles clean and fresh.

It is to be understood that the invention is not limited to the exact form herein illustrated and described, but can be embodied in other forms without departure from its spirit as defined by the appended claims.

I claim:

1. A package for storage, shipment and display of pencils, penholders and like articles, comprising a cardboard support having longitudinal slits terminating in transverse slits providing tongues to support the articles, and a cover extending across the front of the support, having its end portions folded back at the edges of the support and tucked into said longitudinal slits.

2. A package for storing, shipping and displaying pencils, penholders and like arti-

cles, comprising a cardboard support having parallel longitudinal slits terminating in oppositely extending transverse slits defining a pair of opposed tongues, the latter bent 5 forwardly and provided with transversely aligned apertures to receive the articles, and a cover extending across the front of the

support over the articles carried by said tongues, the end portions of the cover being bent back at the side edges of the support 10 and inserted into said longitudinal slits.

In testimony whereof I hereunto affix my signature.

FRED REISS.
